UNITED STATES PATENT OFFICE

ALFRED F. SCIUTO, OF ST. LOUIS, MISSOURI

SPARK PLUG

Application filed January 19, 1929. Serial No. 333,535.

My invention relates to spark plugs and more particularly to spark plugs such as are commonly used to ignite a fluid fuel in internal combustion engines, oil burners, or similar devices.

Heretofore if the sparking points forming the spark gap in spark plugs of this type became carbonized or dirty through any other reason the plug would not operate. So-called intensifiers of various constructions have been used to intensify or raise the voltage of the circuit from the spark coil to such an extent that a spark will be made to jump between even carbonized or fouled plug points. However, such an intensified spark while it will jump across even fouled points is, of course, comparatively thin and, therefore, will not ignite the fluid fuel as quickly as the comparatively thick spark resulting from a plug in which an intensifier is not used.

The object of this invention is to remove this deficiency of structure and to create a spark plug combining the good qualities of both types of spark plugs.

With these and other objects in view my invention is fully shown in the accompanying drawing wherein similar characters are used to designate similar parts: Fig. 1 is a sectional view of a spark plug embodying my invention; Figs. 2 and 3 are cross sections along the lines 2-2 and 3-3, respectively, in Fig. 1; Fig. 4 is a sectional view of a somewhat modified form; and Fig. 5 is a cross section along the lines 5-5 in Fig. 4.

Referring to the figures, Figs. 1, 2 and 3 show my invention adapted to an integral plug while Figs. 4 and 5 show my invention adapted to a usual separable plug. Referring to the form of Figs. 1, 2 and 3 the plug comprises a shell 1 in which is mounted the core 2, of porcelain, mica, or other similar non-conducting material. Between the shell 1 and the core 2 are the usual gaskets 3, preferably of metal. Extending through the core 2 is an electrode 4 which has an enlarged upper end 5 preferably threaded in the upper end of the core 2, for the purpose more fully hereinafter disclosed. On the upper end of the head 5 is a washer 6 fitted over the upper end of the core 2, a lock nut 7 and the parts 8

and 9 between which is clamped the terminal of a wire through which electricity is supplied to the plug. In the lower end of the plug is a pin 10 preferably arranged at substantially right angles to the electrode 4 and spaced therefrom a distance to form a spark gap 11. In this type of plug the shell 1 is grounded and carries sparking points 12 arranged to form spark gaps 13 at the ends of the pin 10. I prefer that the lower end of the hole through the core 2 in which the electrode 4 is mounted be enlarged, as shown, so that both the spark gaps 11 and 13 will be fully exposed to the fluid to be ignited by the plug.

The size of the spark gap 11 may be regulated by loosening the lock nut 7 and then turning the electrode 4 so that the head 5 threaded in the upper end of the core 2 will be raised or lowered, as desired, and in turn the lower end of the electrode 4 will be moved away from or toward the pin 10. The size of the spark gaps 13 may be regulated by bending the sparking points 12 away from or toward the ends of the pin 10.

In the form of my invention shown in Figs. 4 and 5 the core 2 is maintained in position in the shell 1 by a gland nut 14 which may be removed if it is desired to take the spark plug apart. A pair of pins 15 having their inner ends bifurcated as at 16 are provided. Each of the pins forms a spark gap 17 with the lower end of the electrode 4 and a spark gap 13^a with the sparking points 12 carried by the shell 1. The size of the spark gap 17 may be regulated by bending the bifurcated portions 16.

In both forms of my invention it may be readily seen that both the intensifying spark and the resultant intensified spark are exposed to the fluid to be ignited by the plug and, therefore, the plug embodying my invention includes the good features of both types of plugs as heretofore made.

It may be readily understood that a spark plug embodying my invention may be made in various forms and shapes without deviating from the spirit of my invention as included in the claims set forth below.

What I claim as new and desire to secure by Letters Patent, is:—

1. A spark plug comprising a core of non-conducting material, an electrode extending longitudinally through said core, a grounded shell, said core extending downwardly below said shell, a pin extending transversely through said core below said shell with the ends thereof projecting outwardly from the sides of said core, and said pin and said electrode being positioned and arranged whereby a spark will jump from said electrode to said pin and from said pin to sparking points carried by said shell.
- 15 2. A spark plug comprising a core of non-conducting material, an electrode extending longitudinally through said core, a grounded shell, said core extending downwardly below said shell, a pin extending transversely of said core below said shell and below the lower end of said electrode at substantially right angles thereto, and said pin and said electrode being otherwise positioned and arranged whereby a spark will jump from said electrode to said pin and from said pin at 25 both ends thereof to sparking points carried by said shell.
- 30 3. A spark plug comprising a core of non-conducting material, an electrode extending through said core, a grounded shell, a pin extending transversely of said core below the lower end of said electrode and substantially at right angles thereto, and said pin and said electrode being otherwise positioned and arranged whereby a spark will jump from said electrode to said pin and from said pin at 35 both ends thereof to sparking points carried by said shell, and said electrode being arranged in said core so as to be adjustable longitudinally therein whereby the sparking gaps between said electrode and said pin may be regulated.

In witness whereof I have signed my name to the foregoing specification.

ALFRED F. SCIUTO.
